UNITED STATES PATENT OFFICE.

GEORGE W. REAM, OF CANTON, OHIO, ASSIGNOR TO THE BUCHER AND GIBBS PLOW COMPANY, OF SAME PLACE.

RIDING ATTACHMENT FOR HARROWS.

SPECIFICATION forming part of Letters Patent No. 678,370, dated July 16, 1901.

Application filed September 14, 1900. Serial No. 30,051. (No model.)

To all whom it may concern:

Be it known that I, GEORGE W. REAM, a citizen of the United States, residing at Canton, Stark county, Ohio, have invented certain new 5 and useful Improvements in Riding Attachments for Harrows, of which the following is a specification.

My invention relates to improvements in riding attachment for harrows; and the object of the invention is to provide an extremely simple form of attachment which can be readily applied to and removed from any harrow, in which the rider's weight will be carried independently of the harrow, and 15 which will readily accommodate itself to the turning of the harrow.

The invention is illustrated in the accompanying drawings, in which—

Figure 1 is a side elevation of the attachment, showing in dotted lines a sufficient portion of a harrow to illustrate its application thereto. Fig. 2 is an end view. Figs. 3 and 4 are details of the detaching-clip.

In the drawings, A A represent the cross-bars of a spring-toothed harrow of the ordinary or any desired construction.

A bar B carries the seat C, upon which the operator or driver sits, the bar being provided at its forward end with depending arms 30 D, which are secured to the forward cross-bar of the harrow. These arms are preferably formed from a single piece of metal bent into the shape shown and having its central portion bolted to the under face of the end of 35 the bar. These arms carry at their lower ends attaching-clips E, composed of two hinged sections e, having curved portions to fit around the cross-bars of the harrow. At their upper ends they are perforated to permit the passage of a securing-bolt e', which likewise passes through a hole opening in the lower end of the arm, one section lying against each face of the arm. For additional strength and to facilitate assembling each 45 section has a lug e² projecting from one edge thereof, adapted to abut against the edge of the arm.

In order to further steady the seat-supporting bar, while at the same time permitting it 50 and the wheel carried thereby to accommodate

itself to any inequalities in the ground, forked or bifurcated arms F are provided, depending from the bar and adapted to engage the cross-bar of the harrow next in rear. These arms are preferably likewise formed of a single 55 piece or strip of metal curved as shown and having its central portion bolted to the under side of the bar. The bifurcations in the ends are of sufficient length to permit any necessary rise and fall of the beam without any 60 danger of disengaging the forks from the cross-bar. At the rear of the bar is a caster-wheel G, journaled in a trailing or rearwardly-inclined fork G', which has an upwardly-projecting stem g, journaled in the rear end of 65 the bar.

The seat C is mounted upon a rearwardly-inclined spring-support C', so that almost the entire weight of the rider is supported by the wheel and independent of the harrow. 70

It will thus be seen that an exceedingly simple form of attachment is provided easily and securely applied and as easily attached—one in which only a single wheel is used, and yet which will ride steadily, turn easily, and 75 accommodate itself freely to the relative rising-and-falling movement of the harrow due to uneven ground.

Having thus described my invention, what I claim is—

1. The combination with a harrow, of a seat, a supporting-bar therefor, a caster-wheel supporting one end of the bar, a pivotal connection between the opposite end and the harrow and steadyng means located between 85 said pivotal connection and the caster-wheel, substantially as described.

2. The combination with a harrow, of a seat, a supporting-bar therefor, a caster-wheel supporting one end of the bar, a pivotal connection between the opposite end and the harrow an arm depending from said bar intermediately thereof having a vertically-sliding connection with said harrow, substantially as described. 90

3. The combination with a harrow-frame, of a seat, a supporting-bar therefor, a caster-wheel carried at one end of the bar, arms depending from the opposite end thereof pivotally connected to the harrow-frame, and arms 95 100

depending from said bar intermediate of its ends, said arms having sliding connection with said frame, substantially as described.

4. The combination with a harrow-frame comprising a series of cross-bars, of a seat, a supporting-bar therefor, a caster-wheel carried by said bar, arms depending from said bar pivotally connected at their lower ends to one of the cross-bars of said frame and 10 arms carried by said seat-bar having slotted ends guided on one of the cross-bars of the frame to the rear of the first-mentioned cross-bar, substantially as described.

5. The combination with a harrow-frame 15 comprising a series of cross-bars, of a seat, a seat-supporting bar, a caster-wheel carried thereby, a yoke intermediately secured to said bar having an arm depending on each side thereof pivotally connected to said frame, 20 a second yoke secured to said seat-supporting bar having arms depending on each side of the latter with slotted ends, said ends engaging one of the cross-bars of the harrow-frame, substantially as described.

25 6. The combination with a harrow-frame, of a seat, a seat-bar, a caster-wheel, a yoke depending from said bar, steadyng means

and a device at each end of said yoke for pivotally connecting the same to the harrow-frame, said devices comprising two members pivotally connected together having recesses in their opposing faces to receive one of the cross-bars of the frame, the free ends of said members being bolted to the ends of the yoke, substantially as described. 30

7. The combination with a harrow-frame, of a seat, a seat-bar, a caster-wheel, a yoke depending from said bar, steadyng means and a device at each end of said yoke for pivotally connecting the same to the harrow-frame, said devices comprising two members pivotally connected together, said members being duplicates of each other, the upper ends thereof being bolted to the ends of the yokes, each of said members carrying lugs adapted 45 to bear against the edges of the ends of the yokes, substantially as described.

In testimony whereof I affix my signature in presence of two witnesses.

GEORGE W. REAM.
